(57) **CLAIM**

The ornamental design for a portion of a control panel for a construction vehicle with an icon as shown and described.

DESCRIPTION

FIG. 1 is a front view of a portion of a control panel for a construction vehicle with an icon showing our new design; and,

FIG. 2 is an enlarged front view of the portion 2 in FIG. 1 thereof.

The outermost dash-dash broken line illustrates the portion of the control panel that forms no part of the claimed design. The remaining dash-dash broken lines illustrate portions of the control panel for a construction vehicle with an icon in which the design is embodied that form no part of the claimed design. The dot-dash broken lines indicate the location and boundary of the enlarged partial view. None of the broken lines form part of the claimed design.

The icon is shown as surface indicia on the portion of a control panel for a construction vehicle.
